UNITED STATES PATENT OFFICE.

CHARLES BRUNNER, OF PERU, ILLINOIS.

CALISTHENIC APPARATUS.

SPECIFICATION forming part of Letters Patent No. 359,994, dated March 29, 1887.

Application filed December 21, 1886. Serial No. 222,161. (No model.)

To all whom it may concern:

Be it known that I, CHARLES BRUNNER, residing at Peru, in the county of La Salle and State of Illinois, and a citizen of the United States, have invented a new and useful Improvement in Calisthenic Apparatus, of which the following is a full description, reference being had to the accompanying drawings, in which—

10 Figure 1 is a side elevation showing the handle and balls attached for use as a dumb-bell. Fig. 2 is a longitudinal section showing the manner of putting together the parts to be used as a dumb-bell. Fig. 3 is an elevation, 15 partly in section, showing the handle and balls connected for use as a chest-expander. Fig. 4 is a similar view showing the parts in position when pulled or drawn out. Fig. 5 is a detail of the connecting-pin. Fig. 6 is a detail, 20 tail, being an end view of the nut for holding the parts composing the dumb-bell in place.

This invention relates to devices for exercising, and which can be used either as a pair of ordinary dumb-bells or as a chest-expander; 25 and its nature consists in a handle and a pair of balls capable of being connected to form a dumb-bell, or separated to have a ball from each dumb-bell attached to a rope passing through one of the handles and connected to 30 the other handle to form a chest-expander.

In the drawings, A represents a ball or weight forming one end of the dumb-bell. This ball or weight is provided with a screw-threaded hole a, to receive the end of a rod a'.

35 B is a ball or weight forming the other end of the dumb-bell, which ball or weight B is provided with a central hole or passage extending through it for the admission of the rod a'. At one end of the hole or passage is a 40 cut-away portion, forming a recess or countersink to receive a nut, b, which is screwed onto the end of the rod a'.

C is a hollow handle, made of brass or other suitable material, and, as shown, this handle 45 is curved from the center toward both ends, forming at each end a flaring mouth for the reception of the balls or weights A B, and a firmer seating of these balls or weights can be had by forming a circular shoulder, a'', on the 50 balls or weights, against which the mouths of the handle bear, and the formation of this shoulder prevents any slight lateral movement

that might otherwise take place should the rod a' not be fitted snugly in the central passage or hole through the ball or weight B. A hole, 55 c, is provided near one end of the handle C for the reception of a hook, the object of which will be hereinafter explained.

D is a pin corresponding in diameter to that of the rod a', and of a length sufficient to allow 60 it to pass through the ball B, and having on one of its ends a head, d, which fits into the recess formed in the ball B, to receive the nut b when the parts are used as a dumb-bell. On the other end of this pin is formed a hook, 65 d', which projects beyond the surface of the ball or weight B.

E are ropes, each having at one end a hook, 70 e, for insertion in the hole c of one of the handles C, and having at the other end a thimble 75 or ring, e', for attachment to the hook d' of the pin D.

To form a dumb-bell the parts are put together or assembled in the following manner: One end of the rod a' is screwed into the hole 75 a of the ball or weight A. The handle C is then slipped over the rod a', allowing one of its flaring ends or mouths to rest against the shoulder a'' on the ball A. The rod a' is then to be inserted in the passage or hole through 80 the ball or weight B and the nut b screwed tightly onto the end of the rod, which forces the handle C against the shoulders a'' on the balls or weights A B, uniting the parts to form a dumb-bell that can be used the same as an 85 ordinary dumb-bell without danger of the parts becoming loose.

To use the parts as a lifting device for expanding the chest, the nuts b are unscrewed and the ball B and handle C of each dumb-bell are removed. The pins D are slipped into 90 place through the passages in the balls B, the head d of each pin fitting within the recess occupied by the nut b when the parts are used as a dumb-bell, and supporting the weight of 95 the ball. The projecting hook d' is passed through the thimble or ring e' on the lower end of the rope E. The other end of each rope E is then passed through one of the handles C, and the hook e secured in the hole b of the opposite handle C, the handles C being placed 100 to have the ends with the holes b as shown in Fig. 1.

In use the handles C are grasped one in each

hand by the user or operator, with his arms extended in front of him, and are drawn apart by swinging his extended arms horizontally as far as possible, which action of the operator raises the balls or weights from the floor, and at the limit of this movement the parts are in substantially the position represented in Fig. 4. The weights are lowered into position for another pull by the operator swinging his extended arms around to their original position in front of him, and this operation of raising and lowering the weights is to be repeated until the desired amount of exercise has been had.

15 The exercise may be varied by passing the ropes E, when extended or drawn out, over the head of the operator, by keeping one arm stationary and drawing up one weight, and in many other ways that will be readily suggested 20 to the operator.

The curved form of the handles C allows of the ropes being drawn through them with but little friction, and consequently with but little wear on the ropes. This form is also one that 25 affords a firm grasp when used either with the dumb-bells or with the ropes and weights. The ropes are to be of a length adapted to the height of the user.

As shown in Fig. 6, the nut b is provided 30 with holes b', for the insertion of projections of a wrench for screwing the nut into place.

The ball or weight B can be made without

the recess at the end of its central bore or passage in which the nut b and the end d rest, the rod a', in this form of construction, projecting 35 sufficiently beyond the surface of the ball to allow of the nut being screwed thereon, and when the parts are used as a chest-expander the pin D, in this construction, would be made a little longer than shown in the drawings, so 40 that when the head d thereof rested against the surface of the ball or weight B the hook d' would project, as in the construction shown in the drawings and heretofore described. The contact-face of the nut b and head d could be 45 concaved to correspond to the surface of the ball or weight B.

What I claim as new, and desire to secure by Letters Patent, is—

1. The combination of the recessed and 50 shouldered ball A, the recessed, perforated, and shouldered ball B, the hollow curved handle C, the screw-rod a', and the nut b, substantially as described.

2. The combination of the hollow curved 55 handles C C, having holes c c, the ropes E E, provided with hooks e and rings e', the pins D D, having head d and hooks d', and the perforated balls B B, substantially as described.

CHARLES BRUNNER.
